CLAIM

I claim the ornamental design for a watch case, as shown and described.

DESCRIPTION

FIG. 1 is a front elevational view of a watch case showing my new design;

FIG. 2 is a rear elevational view thereof;

FIG. 3 is a right side elevational view thereof;

FIG. 4 is a left side elevational view thereof;

FIG. 5 is a top plan view thereof;

FIG. 6 is a bottom plan view thereof; and,

FIG. 7 is a right front perspective view thereof.

The ornamental design which is claimed is shown in solid lines in the drawings. The structural features depicted by broken lines in FIG. 2 have been shown for the purpose of illustrating portions of the watch case that form no part of the claimed design.
